Frantz and Richards,
ATTORNEYS.

UNITED STATES PATENT OFFICE.

MILTON M. ADLER, OF NEWARK, NEW JERSEY.

PYROTECHNICAL DEVICE.

Application filed October 11, 1923. Serial No. 667,816.

To all whom it may concern:

Be it known that I, MILTON M. ADLER, a citizen of the United States, residing at Newark, in the county of Essex and State 5 New Jersey, have invented certain new and useful Improvements in Pyrotechnical Devices; and I do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 This invention relates, generally, to improvements in pyrotechnical devices; and the invention has reference, more particularly, to an improved pyrotechnical device in the form of a novel detonating firework 20 or fire-cracker.

The invention has for its principal object to provide a detonating firework or fire-cracker comprising a main disc-like body, tablet or lozenge made of a pyrotechnical 25 composition, said body, tablet or lozenge having applied thereto a surface covering in adhering relation thereto consisting of a suitable insoluble material in granular or comminuted form.

30 It has been found that pyrotechnical devices of the general character involved in this invention and made from a pyrotechnical composition containing phosphorus and potassium chlorate, by reason of the disc-like or lozenge shape in which they are generally 35 formed, have frequently been mistaken by children for candy or because of their candy-like appearance have tempted small children to place the same in their mouths, so that illness and sometimes serious poisoning has resulted. In order to avoid such 40 consequences, and to render the devices harmless even if taken into the mouth, while at the same time so altering the general appearance of the device that likelihood of 45 mistaking the same for an article of confection is practically avoided, I have discovered that a granular or comminuted insoluble coating adhesively secured to the surface of 50 the article is very effective; in the first place, because being insoluble the coating prevents the saliva of the mouth from attacking or dissolving the deleterious ingredients of the 55 composition; in the second place, because the roughened character imparted to the sur-

face of the device by the insoluble granular or comminuted covering material renders the same uncomfortable when placed in the mouth; and in the third place because the granular or comminuted covering so changes 60 the appearance of the article that mistakes of the kind referred to are not likely to be made by children.

Another advantage of the novel granular or comminuted coating with which this invention deals, is that the same provides a protective covering for the pyrotechnical composition which shields the same from the effects of ordinary friction produced by one 65 device rubbing upon another when in packages, during transit in shipping, or when displayed for sale and handled, and yet the coating is of such character that an intentionally applied strong friction will wear away the coating so that the inner composition 70 will be quickly exposed to the effects of such strong friction and will consequently readily ignite when such result is desired, and, furthermore, the granular or comminuted coating will not interfere with or prevent 75 desired ignition of the inner composition produced by striking the device a sharp blow, since the effect of a blow of sufficient force will be readily transmitted through the coating to the composition; and, finally, 80 the coating is of such character that it will prevent undue or too sudden disruption or flying apart of the device after ignition.

The invention is illustrated in the accompanying drawings, in which:—

Fig. 1 is a plan view of the pyrotechnical device provided with the novel insoluble granular or comminuted coating; Fig. 2 is a side or edge view of the same; and Fig. 3 is a vertical cross section of the same.

The pyrotechnical composition for obtaining the desired intermittent detonating effects characteristic of the kind of fire-work or fire-cracker involved in this invention, is preferably one in which white phosphorus and potassium chlorate are the combustible and explosive ingredients, said substances being intimately mixed with carbonate of magnesium and red ochre to form a body in which the aforesaid combustible and explosive elements are distributed, a suitable binder such as gum arabic being employed to hold together and harden the mass. The composition is formed into disc-like bodies, tablets or lozenges *a* which when dried and

hardened, may be ignited by either friction or impact, and which when thus ignited are slow burning but adapted to produce during combustion a series of intermittent detonations. Of course, it will be understood that other pyrotechnical compositions than that above described may be employed, and that I do not especially confine myself to the described composition for the purposes of 10 the present invention.

The disc-like bodies, tablets or lozenges of pyrotechnical composition being prepared, I proceed to apply upon the surface thereof and so as to cover the entire area of said 15 surface, a covering or coating *b* comprising a suitable insoluble granular or comminuted material, such, e. g., as sand, saw-dust, metal filings, mineral shiftings or the like. This coating may be applied to the bodies *a* while 20 the same are still somewhat soft so as to be slightly imbedded in the surface thereof and adhesively attached thereto, and I also deem it expedient to mix with the coating material a suitable adhesive material such as dextrine, gum arabic or the like, whereby not 25 only the adhesion of the particles of granular or comminuted material to the body *a* is assured, but also the granular or small particles themselves will be caused to adhere 30 together to provide a substantially permanent coating which efficiently resists accidental displacement, while, however, read-

ily displacing itself under the effects of a comparatively strong friction.

Having thus described my invention, I 35 claim:

1. A pyrotechnical device comprising a body of pyrotechnical composition coated with an insoluble granular material in direct adhesive attachment to the surfaces of said 40 body.

2. A pyrotechnical device comprising a body of combustible detonating composition having its entire surface covered with an insoluble comminuted material in direct adhesive attachment to the surfaces of said body. 45

3. A pyrotechnical device comprising a body of combustible detonating composition having its entire surface covered with a directly applied mixture of insoluble comminuted material and an adhesive agent. 50

4. A pyrotechnical device comprising a body of combustible detonating composition, and a surface coating adhesively attached to said body, said coating consisting of a 55 comparatively fine comminuted inert material, such as sand.

In testimony that I claim the invention set forth above I have hereunto set my hand this 11th day of September, 1923.

MILTON M. ADLER.
